TABLE LAMP

Thomas J. Collings, Railroad Ave.,
Glen Head, N.Y. 11545

Filed Aug. 29, 1967, Ser. No. 8,422

Term of patent 7 years

(Cl. D48—20)

FIG. 2 is an opposite end perspective view with the table lamp parts open.

FIG. 3 is a front elevational view of the rear of the table lamp with the open shade of FIG. 2, and

FIG. 4 is an end elevational view of the table lamp with the open shade.

The dotted line showing in FIGS. 1 and 2 is for illustrative purposes only.

I claim:

The ornamental design for a table lamp, substantially as shown and described.
